UNITED STATES PATENT OFFICE.

ARTHUR T. KUEHNER, OF ELKRIDGE, MARYLAND.

MANUALLY-CONTROLLED STEAM-OPERATED CYLINDER COCK AND DRIFT VALVE.

Application filed September 14, 1921. Serial No. 500,488.

This invention relates to an improved cylinder cock and drift valve for locomotives and seeks to provide a device of this character which will be steam closed under 5 manual control of the engineer but which will automatically open when the steam pressure acting to hold the device closed is manually cut off.

A further object of the invention is to 10 provide a device which will, regardless of the working conditions in the locomotive cylinders, be constantly held closed until the steam pressure closing the device is manually released.

15 The invention has as a further object to provide a device which will, regardless of the presence or absence of steam pressure in the locomotive cylinders, automatically open when the pressure behind it is released.

20 Another object of the invention is to provide a device which may, regardless of the presence or absence of steam pressure in the locomotive cylinders, be closed by steam pressure under manual control.

25 The invention has as a further highly important object to provide a device embodying by-passages for admitting a leakage flow of steam to the cylinders so that when the locomotive is drifting, live steam will 30 be fed to the cylinders for neutralizing and quenching any smoke box gases drawn into the cylinders, scoring of the cylinders as well as formation of carbon therein being thus materially reduced.

35 And the invention has as a still further object to provide a device wherein the leakage flow of steam therethrough will maintain the device warm so that water of condensation in the device will be prevented 40 from freezing.

Other and incidental objects will appear hereinafter.

In the drawings:

45 Figure 1 is a side elevation showing an ordinary locomotive cylinder equipped with the present invention,

Figure 2 is a detail top plan view of the device,

50 Figure 3 is a longitudinal sectional view taken medially through the device showing the cock open,

Figure 4 is a vertical sectional view on the line 4-4 of Figure 3, looking in the direction of the arrows,

55 Figure 5 is a sectional view on the line

5-5 of Figure 3, looking in the direction of the arrows,

Figure 6 is a longitudinal sectional view similar to Figure 3, showing the cock closed, and

Figure 7 is a fragmentary sectional view showing a slightly modified form of cylinder whereby a single cock and valve may be used for both ends of the cylinder.

In carrying the invention into effect, I 65 employ a casing 10 which is provided at its upper side with a cylinder port 11 and formed on the casing adjacent said port are spaced ears 12. The casing is provided with a horizontal passage 13 therethrough, this 70 passage being intersected by the port 11 and, as will be observed, said passage is provided with a reduced outer end portion 14 defining a beveled valve seat 15 at its inner end. The valve seat 15 lies near the outer end of 75 the casing at one side of the cylinder port 11 and leading from the reduced portion 14 of the passage 13 beyond said valve seat is a laterally directed drain opening 16 inclining in a direction away from the valve 80 seat.

Slidably mounted within the passage 13 of the casing is a valve comprising a cylindrical valve body 17 tapered toward its 85 inner end to provide a conical face 18 and terminating in an annular head or piston 19. Formed on the valve body at its outer end is a beveled face 20 adapted to rest flat against the seat 15 of the casing and formed in the periphery of the piston 19 is a plurality of by-passages 21 opening through the end faces of the piston, it being observed in this connection that the piston is formed with flat end faces 22 and 23 respectively. Extending from the outer end of 90 the valve body is a stem 24 slidably fitting in the reduced portion 14 of the passage 13 and formed through the outer end portion of said stem is a diametric slot 25 while adjacent the valve body the stem is formed with a reduced neck 26. Pivoted between the ears 12 of the casing is a bell crank 27 mounted to rock upon a bolt 28 extending through said ears. The short arm of the bell crank is arranged to extend through the 95 casing into the slot 25 of the stem 24 of the valve and is provided with a disc shaped head 29 freely coacting with the end walls of said slot while the long arm of the bell crank is arranged to project outwardly be- 100 105 110

tween the ears 12 and is enlarged at its outer end to provide a weight 30.

In Figure 1 of the drawings, a pair of the devices is shown in conjunction with an ordinary locomotive cylinder 31, a pair constituting a right and left hand cock so that the drain openings 16 of both devices of the pair will be disposed at the outer sides thereof directed away from the locomotive. Threaded into the usual orifices in the ends of the cylinder are short lengths of pipe 32, and as will be at once understood, the casings 10 of the cocks are threaded upon the lower ends of these pipes, the pipes being engaged in the ports 11 of the casings. The cocks are thus mounted in horizontal position beneath the cylinder and extending between the inner ends of the casings 10 of said cocks is a pipe 33. This pipe is formed in sections fitting at their outer ends in the casings and connected therewith by glands 34 while the inner or meeting ends of said pipe sections are coupled by a right and left union 35. Interposed in one of said sections is a T-joint 36 and connected to this joint is a live steam pipe 37 which leads to the cab of the locomotive. Interposed in the pipe at some point convenient to the engineer is an appropriate control valve 38. As will be observed, the valves of the cocks may be displaced from the casings 10 by simply detaching the sections of the pipe 33 and removing the bell cranks 27. To close the cocks, the valve 38 is opened when live steam will be admitted to the casings 10 to act against the pistons 19 of the valves so that the valves will be shifted endwise to engage the beveled faces thereof with the valve seats 15 for cutting off flow through the cocks, the valves, of course, rocking the bell cranks 27 and elevating the weighted ends thereof as said valves are shifted. If no steam pressure is present in the cylinder, the valves will, as will be perceived, close without hindrance. However, provision is made whereby the valves may be closed regardless of the steam pressure present in the cylinder. As will be observed, the end faces 22 of the pistons 19 of the valves are of greater area than the end faces 23 of said pistons. Furthermore, the faces 18 and 23 of each of the valves will tend to balance the action of steam pressure in the cylinder against the valves so that even though the pressure in the cylinder should be approximately equal to the live steam pressure acting against the faces 22 of the valves, the valves will, nevertheless, be shifted outwardly against the action of the weighted bell cranks to closed position and, as will be at once clear, will be constantly held closed regardless of the working conditions in the cylinder, until the steam pressure acting to close the valves is

cut off by manual manipulation of the valve 38.

To open the cocks, the valve 38 is closed. Steam pressure against the faces 22 of the valves will thus be cut off when the weighted bell cranks will automatically shift the valves inwardly to open position. In this connection it is to be particularly observed that provision is made whereby the cocks will, when the valve 38 is closed, automatically open regardless of the presence or absence of steam pressure in the cylinder. Steam pressure in the cylinder acting on the face 23 of the piston 19 of each of the valves will be balanced by a like pressure of the steam on the face 18 of the valve body and the weighted bell cranks 27 are sufficiently heavy to overcome the resistance against the faces 22 of the pistons of steam in the inner ends of the passages 13 so that the cocks will be automatically opened coincident with the closing of the valve 38. Absence of steam pressure in the cylinder will, of course, facilitate opening of the cocks. In the open position of the cocks any water of condensation in the cylinder will, of course, be at once drained therefrom through the drain openings 16 of the cocks.

Attention is now directed to the fact that when the valve 38 is open and the cocks are closed, live steam will leak through the bypassages 21 of the pistons 19. Accordingly, when the locomotive is drifting, live steam will be fed to the cylinder through the cocks for neutralizing and dampening any smoke box gases drawn into the cylinder to thus not only prevent excessive heat in the cylinder with consequent faulty lubrication, but also minimize scoring of the cylinder as well as the formation of carbon therein. Furthermore, since while the cocks are closed, live steam will leak therethrough, the cocks will be maintained warm so that freezing of any water of condensation in the cocks will be prevented.

In Figure 7 of the drawings, I have illustrated a slight modification in the structure of a locomotive cylinder whereby a single cock of the present invention may be employed in conjunction with the cylinder instead of a pair of cocks as illustrated in Figure 1. A portion of a locomotive cylinder is indicated in Figure 7 at 39 and formed on the cylinder at its lower side is a longitudinally directed passage 42 entering the cylinder near the ends thereof. Connected with this passage is one of the cylinder cocks of the present invention, indicated as a whole at 43, a live steam pipe 44 leading to the cock. The pipe 44 corresponds, of course, to the pipe 37 as previously described and, as will thus be seen, the single cock 43 will, in being connected with both ends of the cylinder through the passage 42, serve all the

functions of a pair of cocks connected to the ends of a cylinder as in Figure 1.

Having thus described the invention, what is claimed as new is:

- 5 1. In combination with a steam cylinder, a cylinder cock including a relief valve controlling an outlet passage from the cylinder, a conduit for supplying live steam to the valve, the valve being provided with means having opposed faces of unequal area whereby the valve may be closed against the steam pressure in the cylinder and held closed by steam at the same pressure in said conduit acting on the larger of said faces, and weight 10 operated means constantly urging the valve to open position and automatically operable when the supply of steam to the valve is cut off for opening the valve against steam in said conduit at the same pressure as the 15 steam in the cylinder.
- 20 2. In combination with a steam cylinder, a cylinder cock including a relief valve controlling an outlet passage from the cylinder, a conduit for supplying live steam to the valve, the valve being provided with means having opposed faces of unequal area whereby the valve may be closed against the steam pressure in the cylinder and held closed by steam at the same pressure in said conduit 25 acting on the larger of said faces, weight operated means constantly urging the valve to open position and automatically operable when the supply of steam to the valve is cut off for opening the valve against steam in 30 said conduit at the same pressure as the 35 steam in the cylinder, and means for bypassing to the cylinder a portion of the steam holding the valve closed and operable when the valve is open to release steam trapped in said conduit when said steam supply is cut off.
3. A cylinder cock including a casing provided with a passage therethrough having a larger end portion forming an inlet and a smaller end portion provided with an outlet 40 port, the casing being formed with a relief port opening into the larger end portion of said passage and being provided at the junction of said portions of said passage with a valve seat lying between said ports, a valve 45 slidably fitting in the larger end portion of said passage to engage said seat closing the inlet and said relief port with respect to said outlet port and provided at one end with a stem slidably fitting in the smaller end portion 50 of said passage, the stem being provided with a reduced neck at said outlet port, a piston carried by the opposite end of the valve and slidably fitting in the larger end portion 55 of said passage, said piston being operable by steam pressure entering at said inlet for closing the valve, and a bell crank pivoted upon the casing and provided with a short arm extending into the casing to engage said stem and a long arm forming a weighted 60 lever gravitating to normally shift the valve to open position.

In testimony whereof I affix my signature.

ARTHUR T. KUEHNER. [L. s.]
